FRONT END LOADER

Bernard A. Kuhl, Lakewood, Ohio, assignor to The Thew Shovel Company, Lorain, Ohio, a corporation of Ohio

Filed Apr. 22, 1960, Ser. No. 24,062

7 Claims. (Cl. 214—140)

The present invention relates generally as indicated to a front end loader and more particularly to a front end loader of the type that comprises a pair of longitudinal side booms pivoted at their rear ends to the tractor and at their front ends to the lower rear portion of a material handling scoop; a hoist cylinder for swinging said booms and scoop in a vertical plane about the boom-tractor pivot; and a scoop actuating cylinder and linkage arrangement effective to tip the scoop for scooping up a load and for dumping the load.

It is known, of course, to provide front end loaders having side booms that are of angular form to provide, in digging position, upper rear portions pivotably connected with the tractor and extending generally downward from such pivot; intermediate portions extending generally forwardly between the tractor body and the respective front wheels thereof; lower front portions extending downwardly and forwardly for pivotal connection with the bottom rear portion of the scoop. It is known to provide in equipment of this type, a scoop actuator which comprises, for example, hydraulic cylinders which have one end linked to the respective booms and the other end pivotally connected to the scoop at the rear thereof at points above the boom-scoop connections. Accordingly, by actuating said cylinders, the scoop may be tipped back from digging position to retain a load of material therein, and as the booms are swung upwardly, the linkage aforesaid including the booms, being a departure from true parallelogram linkages, effect a gradual tipping back of the scoop to horizontal maximum load supporting position at a rate less than the angular movement of the booms from digging position to maximum lift position. With the booms thus raised, the aforesaid cylinders are actuated to tip the scoop forwardly and thereby dump the contents thereof.

It is one object of the present invention to provide a front end loader linkage of the character indicated in which the links thereof are disposed within the lateral limits of the respective side booms so as to be protected against dirt and damage.

It is another object of this invention to provide a front end loader of the character indicated which employs curved links which are arranged to have higher deflection rates under load than corresponding straight links heretofore employed in prior art loaders of this character, such curved links, more specifically herein generally S-shaped links, by reason of their higher deflection rates being capable of absorbing shocks and impact loads due to digging action etc. whereby pivot pin wear and breakage is substantially decreased.

It is another object of this invention to provide a front end loader of the character indicated in which the curved links aforesaid are arranged to contribute to the compactness and simplicity of the boom assembly, especially in the regions at the opposite sides of the operator.

It is another object of this invention to provide a front end loader of the character indicated in which the geometry of the scoop and boom linkages is such as to obtain better ranges insofar as hoisting heights and reaches are concerned in relation to the length of the booms and their angles of swing between digging and hoist positions.

It is another object of this invention to provide a front end loader in which the side booms have safety arms or links which, though pivotally connected to the tractor a substantial distance behind the back rest of the operator's

2

seat and steering wheel, preclude injury to the operator and provide for clear side and rear visibility by the operator of the equipment even in the fully raised position of the booms.

5 It is another object of this invention to provide hoist cylinders which, in the digging position of the booms, are disposed in a generally horizontal position and which swing upwardly as the booms are swung upwardly while yet providing a substantial moment arm to enable use of 10 fluid at relatively lower pressure than in known prior art structures.

15 It is another object of this invention to provide a front end loader in which the hoist cylinders are disposed entirely clear of the steering wheels of the tractor to allow a greater wheel cut and consequently a shorter turning radius of the tractor.

20 It is yet another object of this invention to provide hoist cylinders as aforesaid, which are so disposed within the respective booms that in the event of leakage or bursting of the rod packings, the operator is fully protected against injury by hot oil squirting from such defective packings.

25 Yet another object of this invention is to provide a compact front end loader in which all of the component members of the boom-scoop assembly are subjected to digging loads, whereby such loads are distributed among the said members to thus avoid any unduly bulky components.

30 Still another object of this invention is to provide a front end loader which, in the maximum hoist position, has cooperating stops on the boom and the scoop effective, when the scoop is tilted to dumping position, to shake or jar the scoop so as to free the contents thereof for sliding out.

35 Still another object of this invention is to provide a front end loader in which the scoop actuator provides the dumping stops in the maximum reach position of the boom but a resilient connection is provided between the actuator and the scoop so that the impact of dumping loads on the actuator is substantially lessened.

40 Still another object of this invention is to provide a front end loader which is of simple and compact form with relatively few parts and which consequently is less expensive to manufacture and has fewer places of wear.

45 Other objects and advantages of the present invention will become apparent as the following description proceeds.

To the accomplishment of the foregoing and related ends, the invention, then, comprises the features herein-after fully described and particularly pointed out in the claims, the following description and the annexed drawings setting forth in detail a certain illustrative embodiment of the invention, this being indicative, however, of but one of the various ways in which the principle of the invention may be employed.

50 In said annexed drawings:

55 FIG. 1 is a side elevation view of a front end loader according to the present invention, the boom and scoop being shown in its lowered digging position in full lines in which position the scoop is held while the loader is driven into a pile of gravel, sand or other material which it is desired to scoop up and load into a truck or to dump elsewhere, FIG. 1 also showing in dot-dash lines the initial tilt-back position, wherein the material is scooped into the scoop as the loader continues to move into the pile of material, and also showing in dot-dash lines a portion of the scoop in the position it assumes as the boom is raised;

60 FIG. 2 is a longitudinal section view showing the loader linkage in its digging position, such section having been taken along the line 2—2, FIG. 3;

65 FIG. 3 is a top plan view of one of the side booms of the loader; and

FIGS. 4 and 5 are side elevation views similar to FIG. 1 respectively showing the positions of the loader components when the boom is raised to maximum height and when the boom is lowered from maximum height to provide for added reach.

Referring now more specifically to the drawings, and first to FIG. 1, the front end loader herein comprises a tractor 1 having front and rear wheels 2 and 3 all of which are engine-driven and of which the rear wheels 3 are the steering wheels actuated by the steering wheel 4 provided near the front end of the tractor 1. Behind the steering wheel 4 is the operator's seat 5 which includes the usual back rest 6. At the front end of the tractor 1 is a block of rubber 7 or the like, that constitutes a bumper so that the tractor may be driven against the side of a truck body when the boom 8 is in the raised position containing a load of material in the scoop 9 thereof which it is desired to dump into the truck body.

The loader herein comprises a pair of parallel angular booms 8 which have their rear and upper ends pivotally connected by pins 10 to the brackets 11 affixed on opposite sides of the tractor 1 at a zone which is spaced a substantial distance to the rear of the back rest 6 of the operator's seat 5 and a substantial distance below the top edge of the back rest 6. The lower front ends of the booms 8 are pivotally connected by pins 12 to the lower rear portion and adjacent the ends of the scoop 9.

As best shown in FIGS. 2 and 3, each boom 8 comprises a pair of parallel side plates 14 joined together by a top web plate 15 which in the digging position of the boom 8, extends downwardly and forwardly from adjacent the boom pivot 10 and by another top web plate 16 of generally V-shaped transverse cross-section which extends downwardly and forwardly along the downwardly and forwardly extending front portion of the boom 8 at a zone spaced rearwardly from the boom-scoop pivot 12. There is also a rear web 17 disposed across the rear edges of the side plates 14. The front end portions of the booms 8 are joined together as by a transversely extending tubular brace member 18 having its ends securely attached, as by welding, or equivalent expedient, to the respective booms 8.

Pivottally connected to each boom 8 by pin 19 between the top webs 15 and 16 is an S-shaped link 20, one end of which, in turn, is pivotally connected by the pin 21 to the cylinder 23 of the double acting scoop-actuating piston-cylinder assembly 24. The piston rod 25 of the scoop-actuator 24 is pivotally connected by the pin 26 to the scoop 9 at a zone which is substantially directly above the connection of the boom 8 with the scoop 9 when boom and scoop are in FIG. 2 digging position. In this condition of the parts, the scoop-actuator 24 is partly extended so that when the piston rod 25 is fully retracted in the cylinder 23, the scoop 9 will be tilted back about 37° up from horizontal as shown in dot-dash lines in FIG. 1. As the scoop 9 is thus tilted back, the cylinder 23 swings down about pin 21 but clears the web 16 by reason of the special shape of the latter. Normally, the operator drives the tractor 1 into the bottom of the pile while the boom 8 is down and the scoop 9 is in digging position, as shown in full lines in FIG. 1, and after the scoop 9 has penetrated the pile, the operator actuates an appropriate valve (not shown) to fully retract the scoop actuator 24 to the aforesaid 37° position while the tractor 1 continues to move into the pile. At the same time, the operator actuates another valve (not shown) to swing the boom 8 up about the boom pivot 10. As the boom 8 swings up, the scoop 9 tilts back but not in direct relation to the angle of swing of the boom 8 by reason of the provision of a linkage mechanism hereinafter described.

In order that the scoop 9 be tilted back at a slower rate than the rate of angular movement of the boom 8

to thus enable raising of the boom to a greater maximum height, the lower end of the S-shaped intermediate link 20 is pivotally connected by the pin 27 to the lower front end of another S-shaped link 28 which has its upper rear end pivotally connected by a pin 29 to a bracket 30 which is fixed on the tractor 1 preferably at a point below and forward of the boom pivot pin 10.

This longer link 29 is of the same general shape as the boom 8 so as to be substantially entirely within the side plates 14 in all positions of the boom 8.

It is to be noted that the pairs of pins 10 and 29 and 19 and 27, and the pairs of pins 21 and 19 and 26 and 12, do not constitute the corners of parallelograms, and that by reason of their particular disposition as herein shown,

the swinging of the boom 8 from digging position (FIG. 1) to the maximum hoist position (FIG. 4) through an angle of say about 74°, the scoop 9 only swings about 24°, from its 37° position in the tilted back digging position to the 61° maximum height and capacity position.

In other words, as clearly shown in FIG. 4, the intermediate S-shaped link 20 has been swung clockwise during the upward swinging movement of the boom 8 through the long S-shaped link 28 due to swinging of the front end of link 28 about the axis of the pin 29 while the boom short link pivot 19 swings about the axis of the boom pivot 10. In the maximum height position, the scoop 9 is in maximum load-carrying position and when it is desired to dump the contents of the scoop the operator actuates a valve (not shown) to open the rod end of the

scoop-actuating cylinder 23 to a vent through large size tubing, and, at the same time, to introduce fluid under pressure from an engine-driven pump (not shown) into the head end of the cylinder 23, whereby the scoop 9 will be swung clockwise about its pivot connection 12 to the

tip of the boom 8. As the scoop 9 swings to dumping position, a stop 31 on the scoop 9 engages a stop 32 on the boom 8, whereby to jar the contents of the scoop 9 for ready sliding therefrom. In this dumping position, the angle A from horizontal is preferably about 51°.

In this FIG. 4 dot-dash line dumping position of the scoop 9, the lip 34 of the scoop is 3'0" from the front peripheries of the wheels 2 (dimension B) and nearly 10' from the ground (dimension C). When it is necessary to reach further as into a wide body truck or railroad car,

the boom 8 may be lowered about 12° to the FIG. 5 position in which the dumping position angle D is about 46° and the lip 34 thereof is spaced about 4'5½" (dimension E) from the front peripheries of the wheels 2 while the lip 34 is 8'6" (dimension F) from the ground.

At the maximum hoist position of the boom 8 and with the scoop 9 in dumping position with the stops 31 and 32 engaged with one another, the piston 25 in the cylinder 23 is not quite at the end of its stroke, whereby no shock loads are imposed on the cylinder end cap 35 by the piston 25.

However, in other positions of the boom 8, the stops 31 and 32 do not quite engage. Therefore, in order to absorb inertia shock loads of the scoop 9 that otherwise would be transferred from the piston 25 to the end cap

35 of the cylinder 23, there is provided a rubber bushing 36, at least around the pin connection 26 of the piston rod 25 to the scoop 9.

As aforesaid, the indentation in the web 16 of the boom 8 accommodates the cylinder 23 as when the scoop 9 is tilted back from the digging position. The slot 37 in the lower front end of the web 16 accommodates the scoop supports 38.

The hoist cylinder 40 is preferably disposed in generally horizontal position and substantially entirely within the confines of the side plates 14 of the boom 8 when the latter is in digging position. Thus, the piston rod 41 of the hoist cylinder 40 is connected by the pin 42 to a bracket 43 on the tractor 1 at a point spaced a substantial distance below the boom pivot 10 and the long S-arm pivot 29. As shown, the top and bottom portions 45 and

75

46 of the long S-arm 28 are cut away to accommodate the hoist cylinder 40 which extends between the opposite sides of said long S-arm 28. The cylinder 40 near its rod end has a trunnion 47 affixed thereto which is journalled in the opposite side plates 14 of the boom 8 at a region which is below and forward with respect to the boom and long arm pivots 10 and 29, the side plates being reinforced as by bosses 48 welded thereto. Accordingly, when the boom 8 is raised, the operator actuates a valve (not shown) to allow fluid under pressure to enter the head end of the cylinder 40, whereby the cylinder is moved with respect to the piston 41 to swing the boom 8 about its pivot 10. Even in the maximum height position of the boom 8 (FIG. 4) the hoist cylinder 40 acts through a substantial moment arm G about $\frac{2}{3}$ of the maximum) so as not to require the use of extremely high pressure fluid or an unduly large cylinder. It is further to be noted that in the maximum hoist position of the boom 8 the rod packing 49 is disposed within the side plates 14 and beneath web 15 to thus protect the operator from injury in the event of leakage or bursting of such rod packing.

Another feature of the present invention is that by reason of the disposition of the boom pivot 10 a substantial distance to the rear of and below the top edge of the back rest 6, the boom 8 in its maximum hoist position may extend forwardly and upwardly as shown in FIG. 4 without impairing the operator's lateral visibility while seated on the seat 5.

From the foregoing, it can be seen that the present invention is of simple and compact form and enables lifting of the scoop to relatively great heights while providing adequate reach in relation to the length of boom 8. Also, a relatively small hoist cylinder 40 may be employed in nesting relation with the boom 8 and S-shaped link 28. Furthermore, the links 20 and 28 are shaped to clear each other and the boom 8 aside from the higher deflection rates thereof under load than corresponding straight links. In the digging position, and with fluid under pressure in the hoist and scoop actuating cylinders 40 and 23, the digging loads are distributed among all of the components of the front end loader herein whereby none of the components need be of heavy and bulky form. Even the booms 8 are of S-shaped form having higher deflection rates than comparable straight booms extending downwardly and forwardly from the boom pivots 10. This yielding of the components herein prevents application of heavy shock or impact loads on the pins thereof with consequent greater pin life.

Although in the present case a portion of the loader arm geometry is disposed to the rear of the operator, it is to be understood that the loader herein may be mounted on any desired portion of the tractor 1 with, for example, the boom pivot 10 disposed forwardly with respect to the operator's seat 5.

Other modes of applying the principle of the invention may be employed, change being made as regards the details described, provided the features stated in any of the following claims, or the equivalent of such, be employed.

I therefore particularly point out and distinctly claim as my invention:

1. A front end loader comprising a mobile tractor having ground-engaging propelling means and a forwardly facing operator's seat from which the operator may control the movements of said tractor; and a forwardly extending material handling assembly and actuating means therefor pivotally mounted on said tractor for swinging in a vertical plane from a lower material pickup position to an upper hoist and dump position; said assembly comprising a pair of hollow booms having rear portions which are pivotally connected to the respective sides of said tractor rearward of said seat and which, when said booms are in such lower position, extend downwardly and forwardly from such boom pivot, said booms also having

front portions disposed forwardly of the front end of said tractor and close to the ground when said booms are in such lower position; a material handling scoop pivotally connected to the front ends of said booms for tilting movements about a horizontal axis for scooping material therein and for dumping such material therefrom; and a three-part linkage associated with each boom for tilting said scoop to different angular positions with respect thereto, said linkage comprising a first link disposed substantially in its entirety within said boom and pivotally connected at one end to said tractor at a point below the boom-tractor pivot, an intermediate link pivotally connected between its ends to an intermediate portion of said boom, and a third variable length link pivotally connected at its respective ends to said scoop in radially spaced relation to the boom-scoop pivot effective to tilt said scoop to different angular positions relative to said boom in response to change in length of said third link and to one end of said intermediate link, the other ends of said first and intermediate links being pivotally connected together, the pivot connections of said boom and said first link to said tractor and of said intermediate link to said boom and to said first link defining the corners of an articulated quadrangle which changes the angular position of said scoop with respect to said boom as the latter is swung about the boom pivot, said first link being of generally S-shaped form curving downwardly and forwardly from such one end and thence downwardly and forwardly toward such other end when said boom is in such lower position, and wherein said intermediate link is of generally S-shaped form curving upwardly and forwardly from such other end to its pivot connection with said boom and thence extending upwardly curving successively rearwardly and forwardly toward such one end.

2. The front end loader of claim 1 wherein a hoist cylinder is provided in operative association with each boom to swing said assembly as aforesaid, said cylinder having one end pivotally connected to said tractor at a point below the boom and first link pivotal connections with said tractor and extending generally horizontally into said boom when the latter is in such lower position, and having an intermediate portion pivotally connected to said boom to swing the latter upwardly when said cylinder is extended.

3. The front end loader of claim 1 wherein a hoist cylinder is provided in operative association with each boom to swing said assembly as aforesaid, said cylinder having one end pivotally connected to said tractor at a point below the boom and first link pivotal connections with said tractor and extending generally horizontally into said boom when the latter is in such lower position, and having an intermediate portion pivotally connected to said boom to swing the latter upwardly when said cylinder is extended, said first link being formed with an opening between its ends through which the other end of said cylinder extends.

4. A boom and scoop assembly comprising a pair of hollow generally S-shaped booms which, in their lower material pickup position, extend downwardly and forwardly from their upper ends and thence downwardly and forwardly toward their lower ends, a support to which the upper ends of said booms are pivotally connected for swinging in vertical planes from such lower position to an upper hoist and dump position, a scoop pivotally connected to the front ends of said booms for tilting movements to different angular positions with respect to said boom to scoop material therein, to hoist such material responsive to upward swinging of the front ends of said booms, and to dump such material therefrom, and a pair of link assemblies extending from pivot points on said support through the respective booms to pivot points on said scoop radially spaced from the respective boom-scoop pivots, said link assemblies including first links of generally S-shaped form extending substantially longitudinally within said booms curving downwardly and for-

wardly from pivotal connections at their upper ends with said support and thence curving downwardly and forwardly toward their lower ends, second links having lower ends pivotally connected to the lower ends of the respective first links and having intermediate portions pivotally connected intermediate the ends of the respective booms, and third variable length links having their ends pivotally connected to the upper ends of the respective second links and to said scoop as aforesaid operative when increased in length to tilt said scoop to material dump position, the pivotal connections of said booms and first links with said support, of said second links with said booms, and of said first and second links with each other defining the corners of articulated quadrangles effective to tilt said scoop with respect to said booms as the latter are swung upwardly from such lower position to an upper hoist position from which the material therein may be dumped by extending said third links, said second links being also of generally S-shaped form curving upwardly and forwardly from their lower ends and thence extending upwardly and curving rearwardly and forwardly toward their upper ends when said booms are in such lower position.

5. The assembly of claim 4 wherein extensible hoist means are operatively associated with the respective booms to swing them from lower to upper position, said hoist means extending generally horizontally within the respective booms in the lower position of the latter and having rear ends pivotally connected to said support at points below the respective boom and first link pivot connections with said support and having intermediate portions pivotally connected to the respective booms.

6. The assembly of claim 4 wherein extensible hoist means are operatively associated with the respective booms to swing them from lower to upper position, said hoist means extending generally horizontally within the respective booms in the lower position of the latter and having rear ends pivotally connected to said support at points below the respective boom and first link pivot connections with said support and having intermediate portions pivotally connected to the respective booms, and wherein said first links have openings between their ends through which the front ends of the respective hoist means extend when said booms are in such lower position.

7. A front end loader comprising a mobile tractor having ground-engaging propelling means and a forwardly facing operator's seat from which the operator may control the movements of said tractor; and a forwardly extending material handling assembly and actuating means

therefor pivotally mounted on said tractor for swinging in a vertical plane from a lower material pickup position to an upper hoist and dump position; said assembly comprising a pair of hollow booms having rear portions which are pivotally connected to the respective sides of said tractor rearward of said seat and which, when said booms are in such lower position, extend downwardly and forwardly from such boom pivot, said booms also having front portions disposed forwardly of the front end of said tractor and close to the ground when said booms are in such lower position; a material handling scoop pivotally connected to the front ends of said booms for tilting movements about a horizontal axis for scooping material therein and for dumping such material therefrom; and a three-part linkage associated with each boom for tilting said scoop to different angular positions with respect thereto, said linkage comprising a first link disposed substantially in its entirety within said boom and pivotally connected at one end to said tractor at a point below the boom-tractor pivot, an intermediate link pivotally connected between its ends to an intermediate portion of said boom, and a third variable length link pivotally connected at its respective ends to said scoop in radially spaced relation to the boom-scoop pivot effective to tilt said scoop to different angular positions relative to said boom in response to change in length of said third link and to one end of said intermediate link, the other ends of said first and intermediate links being pivotally connected together, the pivot connections of said boom and said first link to said tractor and of said intermediate link to said boom and to said first link defining the corners of an articulated quadrangle which changes the angular position of said scoop with respect to said boom as the latter is swung about the boom pivot, said booms and scoop being provided with interengageable stops to jar said scoop when said third link is extended in an upper position of said assembly, and wherein the third link-scoop pivot includes a yieldable component effective to reduce inertia loads on said third link when fully extended in an intermediate position of said assembly and prior to interengagement of said stops.
